SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN

MECHANISM FOR TIMING MIXING AND OTHER OPERATIONS

Application filed April 30, 1926. Serial No. 105,798.

This invention relates generally to mechanism for timing mechanical operations; although the embodiment thereof herein illustrated and described has been devised particularly for use in connection with concrete mixing apparatus.

The restrictions placed upon users of concrete mixing machinery are becoming more and more severe, as investigation proves that the time element in mixing concrete is an exceedingly important factor.

This invention has for one of its objects to produce an improved timing mechanism, or batch meter, as it is called when used in connection with concrete mixing machinery, that shall not commence its measuring operation until certain preliminaries are completed; although the mechanism may be set for operation for an indeterminate length of time preliminary to its beginning its timing or measuring function. Thus, applied to a concrete mixing machine, the timing mechanism or batch meter may be set when the operation of charging the mixing drum begins. But the timing of the mixing period does not commence until all of the aggregates have entered into the mixing drum, or, which is practically the same thing, until the loading device, whatever its character, begins its return movement.

Another object of the present invention is to produce a batch meter or timing mechanism that operates accurately under all conditions, that may be adjusted for a longer or shorter period of timing, and whose functions and operations are not affected by the position of the mechanism relative to the horizontal.

A further object of the invention is to produce a timing mechanism or batch meter that gives a signal or alarm the instant it begins to operate as a timing device, and another signal or alarm at the end of the timed period, when it completes its operation.

Further objects of the invention are to improve the apparatus in its various details and features of construction, which will be hereinafter pointed out.

In the drawings—

Figure 1 is a side view, largely diagram-

matic, of a concrete paving machine, showing one way of adapting the present invention thereto.

Fig. 2 is a diagrammatic view in side elevation illustrating another manner of applying the invention to a concrete mixing apparatus. 55

Fig. 3 is an end view of a batch meter embodying the present invention, parts of the end wall of the enclosing casing being broken away to expose to view the apparatus within. 60

Fig. 4 is a front view of the timing apparatus, the parts being represented in normal position, that is, the position which they should occupy when the material is not being mixed. 65

Fig. 5 is a front view of the timing apparatus showing the parts in set position but before the timing operation has begun. 70

Figs. 6, 7 and 8 are vertical sectional views all taken on the line VI—VI, of Fig. 9, and parts being omitted for the sake of clearness; Fig. 6 showing the parts in normal position, Fig. 7 in the position they occupy when the apparatus is set, and Fig. 8 representing the position of the parts at the completion of the mixing operation. 75

Many of the parts of the paving machine to which the invention is applied have been omitted from the drawings, which are largely diagrammatic as to such machine. Referring to the drawings, A indicates a rotating mixing drum suitably mounted upon a movable support, B the charging skip therefor, pivotally supported at b, and C the discharge chute. The latter is of the power-driven type, the mechanism for controlling and moving the discharge chute being mounted within in a casing D. This mechanism may be like that illustrated in Patent 1,415,411 of May 9, 1922, to Samuel Shafer, Jr., and therefore is not illustrated in detail, it being deemed sufficient to show only the exposed handle F by which the operating mechanism for the discharge chute is controlled and put into connection with the power shaft that operates it.

E represents the casing within which is mounted the batch timing mechanism constituting the present invention.

This mechanism is arranged to be intermittently operated, being set when the charging of the mixing drum takes place, but not started into operation until such charging operation has been fully completed. Thus, as illustrated in Fig. 1, when the loading skip B comes to position to deliver its charge into the mixing drum, as represented in dotted lines, it impinges against the end of a push rod 1 that is connected with the set lever or arm 2 of the timing mechanism or batch meter. The normal positions of the push rod 1 and operating lever, that is, the positions they occupy when the batch timer is at rest, are represented in Figs. 1 and 4. When the skip comes to charging position the rod is moved toward the left and the arm or lever 2 is turned in the direction of the arrow Fig. 4, and into the position represented in Fig. 5.

A spring 3, preferably located within the casing E, is connected with the arm 2 and tends to move it and its associated parts into normal position.

The arm 2 is supported upon a shaft 34. The connection of the arm with the batch timing mechanism, which it directly moves, is not rigid or fixed, but rather is through a spring, in a manner and for a purpose that will be presently described. As the skip comes to loading position and the arm 2 and the shaft with which it is connected are moved, the batch timing mechanism is set, but it does not begin to operate until the skip has completely discharged, and the entire batch of materials to be mixed has been delivered into the mixing drum, which completed operation is evidenced by the attendant starting the skip upon its return or

downward movement, whereupon the batch timing mechanism starts, and an alarm or signal is given to notify that the timing of the mixing has begun.

The connection between the arm 2 and the mechanisms it controls is through a spring 16 (Fig. 10) located in a cylindrical spring box 38, that is mounted, so as to be free to turn, in a bearing 40, shown as being integral with the rear wall of the casing E. The spring box has also bearing upon the shaft 34, relative to which it is freely rotatable. One end of the spring 16 is secured to the casing or box 38, and the other end to a sleeve 35 surrounding the shaft 34, and also free to turn thereon. The sleeve has bearing in a face plate 39 that covers the spring box 38, and is provided exteriorly of said face plate with a head 36 that is peripherally notched. The arm 2 is mounted upon a disc 28 keyed to the shaft 34, being secured thereto frictionally so as to permit easy angular adjustment. The disc carries a pawl 37, (Fig. 20) the free end of which is adapted to enter the notches of the head 36 of the sleeve 35, this arrangement providing for adjusting the tension of the spring, whose office is to permit an overrunning of the arm 2 after the cylindrical box 38, and the disc 4 which it carries, have been arrested, without liability of straining or breakage of parts. The disc 4 just referred to is located within the casing E, is supported concentrically upon the shaft 34, and is turned by the spring box 38 of which it is preferably an integral part, constituting the inner end thereof, and being of greater diameter than the portion of the box mounted in the bearing 40. The peripheral edge of the disc 4 has formed in it two notches or recesses, 6 and 31, (Figs. 6 to 8) and is formed with or carries two projections 32 and 33. It also carries an inwardly extending pin 8 and a pin that serves as the pivotal connection for a link 57 uniting the spring 3 with the disc.

I will next describe the manner in which the timing mechanism is set upon the movement of the arm 2 from the position shown in Figs. 1 and 4 to that represented in Fig. 5, and I may here state that such timing mechanism includes a dashpot of peculiar construction.

10 designates a shaft suitably supported and in axial alignment with the shaft 34, see Fig. 10. At its end toward the disc 4 it carries an arm 9, which is keyed thereto and is located in position to be acted upon by the pin 8 projecting from the disc, the pin engaging with the arm when the disc is being turned from normal position to the set position, but separating from the arm and traveling at a much more rapid rate as the parts return to normal positions. The shaft 10, at the end opposite the arm 9, carries a large disc 11, (Figs. 4, 5 and 9) a portion of the

periphery of which is formed into a segmental gear that meshes with a smaller segmental gear 12 mounted upon a shaft 64. This train of gearing operates to set the batch timing mechanism when the loading skip comes to discharging position, and is then freed from connection with the latter when it is lowered. The gear 11 is connected, by a link 23, with a batch counter G, so that at each operation of the timing mechanism the counter registers that a batch of concrete has been mixed.

65 indicates the cylinder of the timing mechanism suitably supported within the casing E and formed with a longitudinal bore in which operates a piston 67, (Figs. 12, 18 and 19) the cylinder containing a suitable liquid such as oil or glycerine, that circulates as the piston is reciprocated, flowing freely from one side of the piston to the other when it moves in one direction, but the flow being restricted when the movement of the piston is in the opposite direction. Plugs 73 at the opposite ends of the cylinder close the bore in which the piston operates. There is a longitudinal passage 68 through the piston, permitting free flow of the liquid from one side of the piston to the other when it is moved in one direction. A stop valve 15 preferably of spherical shape serves to prevent flow of liquid through the passage 68 when the piston is moved in the opposite direction, this valve being held to its seat by a spring 69. A by-pass 70 within the body of the cylinder 65 conducts the fluid around the piston. In this by-pass is arranged a valve 24 through which is a restricted opening 75. Upon the stem of this valve is mounted an arm 25, (Figs. 14 and 15) the free end of which is movable over the face of a segment 26 attached to the cylinder 65. By moving the arm the valve is adjusted to vary the size of the exposed area of the opening through the valve 24. The arm may be set in the position to which it may be moved by a set screw 27. There is a transverse opening 29 between the by-pass 70 and the central bore of the cylinder 65, and a radial opening 71 through the piston 67 communicating with the longitudinal passage 68 therein. These two openings, 29 and 71, are so related that they register as the piston is terminating its return movement, and just as the timed mixing period is completed, thus forming a cut-off or shunt passage between the opposite ends of the piston, short-circuiting the valve 24. The opening into the by-pass 70 through the end of the cylinder is closed by a plug 72.

66 The piston 67 is provided with a stem or rod formed into a rack 14 with which engages a pinion 13 on the shaft 64. The forward end of the stem of the piston is provided with a head 74 that serves as a guide therefor, such head being perforated to permit easy passage

of the liquid confined within the cylinder as the piston is moved.

The cylinder 65 is exteriorly provided with a pair of lugs 66 through which extends the shaft 10 carrying the gear 11 and between which is located a coiled spring 76 (Fig. 13) that operates to move the piston in one direction. One end of this spring is connected with the cylinder 65 or with the lugs 66, as may be most convenient, and the other end with a sleeve 77 mounted on and adjustable circumferentially about the shaft 10. This sleeve is supported so as to turn freely in one of the lugs 66, which may serve as a bearing therefor, and is formed with a notched head 81 with which engages a pawl 82 carried by the gear 11, which arrangement serves as a connection between the sleeve and the pinion, that is rigid for working conditions but permitting adjustment of the sleeve in order to vary the tension of the spring 76, as may be required. The adjusting means for this spring are similar to those which have already been described in detail for the spring 16 connected with shaft 34, and hence need not be further described in detail. When the shaft 10 is turned by the coming of the skip to loading position, through the train of mechanism including the arm 2 and the shaft 34, as has been described, the piston is quickly moved back, through the train of gearing including gear wheels 11 and 12, the shaft 64, and the pinion 13 that engages with the rack 14 on the stem or rod of the piston. When the skip returns to its loading position to be again charged with aggregates, the connection between the shafts 34 and 10 is broken by recession of the pin 8, whereupon the spring 76 acts to turn the shaft and return the piston to its forward position, this causing circulation of the liquid within the cylinder 65 through the by-pass 70 which is restricted by the valve 24 so that the movement of the piston is relatively slow, depending upon the size of the available opening through the valve 24 and upon the force of the spring 76.

78, 79 (Figs. 11, 13 and 16) are lugs projecting from the cylinder 65. These are internally screw-threaded to receive bolts or screws by which the cylinder is supported within the casing E. 79 is another lug in which is supported a stud shaft 80 (Figs. 4, 5 and 9) on which is mounted a locking latch or trigger 18.

I will now describe the mechanism for giving the signals to indicate, first, when the batch timer begins to operate, and, second, when it completes its operation, the first signal notifying the attendant that the mixing of the batch has commenced, and the latter that it has been completed, or rather, has continued for the length of time measured by the batch meter.

Referring to Figs. 3 to 8, 41 indicates a bell, which is typical of a device for giving

the signals just referred to. It is shown as supported below the casing E enclosing the batch meter. The mechanism for operating the bell may be variously constructed, that which I illustrate comprising a reciprocating striker mechanism 42 that is acted upon by an angular bell lever 43. A lever 44, herein termed the trigger lever, is supported upon the same shaft as the bell-operating lever 43 and carries at its forward end the trigger 5, the head or cam-shaped end 58 of which bears upon the peripheral edge of the disc 4 and is adapted to enter the recesses, 6 and 31, when these come opposite to the head. A spring 56 is interposed between the trigger 5 and the trigger lever 44, and tends to force the head end of the trigger against the periphery of the disc 4, hence being under greater tension when the head end of the trigger is moved away from the center of the disc than when it is allowed to approach such center, as when the cam-shaped portion of the head enters one of the recesses, 6 or 31.

The normal positions of the parts being described, that is, the positions they occupy when the loading skip is down, and the batch meter is at rest, is represented in Fig. 6. Referring to this view it will be seen that the head of the trigger 5 lies within the recess 31 of the disc 4, and hence the spring 56 is under little tension, that the striking mechanism 42 is elevated, and that the pin 8 is in engagement with the arm 9 on the shaft 10.

As the disc 4 is turned in the direction of the arrow, by the skip engaging with the push rod 1, the spring 3 is put under tension, and the arm 9 is rotated, setting the timing mechanism. During the first part of its movement the arm 9 passes the head of the trigger 5, moving the latter out of its path, to be immediately restored to engagement with the periphery of the disc 4 by the spring 56. The pivotal connection of the link 57 with the disc 4 has an angular movement corresponding with that of the disc, but toward the end of the movement of the latter an offset portion of the projection 32 of the disc comes into engagement with the link 57 and turns it upon its pivot, as indicated in Fig. 7, thus causing the end of the link to which the spring 3 is connected to have an accelerated movement during the latter part of the rotation of the disc 4, with a correspondingly rapid increase in the tension of the spring 3. The extent of the angular movement given to the disc 4 is determined by the positions of the projections 32 and 33. A stationary pin 59 located between and in the paths of movement of these projections serves as an abutment against which they respectively bear, the projection 33 engaging with the pin when the parts are in normal position, Fig. 6, and the projection 32 engaging therewith when the parts are in position to set the timing mechanism. The

parts remain in the position represented in Fig. 7 so long as the skip is raised, but when, after it has delivered its complete charge into the mixer, it is lowered, the spring 3 rapidly restores the disc 4 to normal position. As it does so the pin 8 leaves the arm 9, which follows slowly as the timing mechanism operates. The head of the trigger 5, as has been noted, lies within the recess 6 when the parts are in set position, Fig. 7, so that as the disc begins its reverse movement it carries with it the trigger, and the trigger lever 44 and the bell lever 43 are moved, setting the striking mechanism 42 of the bell in position to sound a signal. After a short movement of the trigger, sufficient to set the striking mechanism as just described, the cam surface of the trigger head 58 comes into engagement with a fixed pin 7, which causes the trigger to rock upon its pivot, putting the spring 56 under tension and at the same time withdrawing the projecting end of the head from the recess 6. This movement causes the bell striking mechanism to be operated, and a signal is given, indicating that the timed mixing operation has begun. As soon as the signal has been given, and the recess 6 in the disc 4 passes beyond the head 58 of the trigger, the bell striking mechanism 42 rises, but remains in set position until the recess 31 comes opposite the head when the parts of the bell striking mechanism assume the positions indicated in Fig. 6 where they remain until the arm 9 approaches the completion of its movement, indicating that the timed mixing operation is about completed. The arm is arranged to engage with the head 58 of the bell trigger and move it in a downward direction and toward the pin 7, Fig. 8, when the striking operations that have been described are repeated, the signal taking place at the moment the timed mixing operation is completed, and notifying the attendant that the batch of concrete within the drum may be discharged.

It is a requirement in many concrete mixing machines that the delivery chute shall be locked in inactive or non-delivery position during the entire mixing period, and I have provided means for effecting such locking controlled by the batch timing mechanism that I have described.

17 (Figs. 4 and 5) indicates a rod or bolt that is the element of the discharge chute locking means which enters the casing E. This rod is represented as suitably supported within the casing so as to be movable upon right lines, and has a spring 22 acting upon it, tending to move it downwardly, that is, into locking position. The rod carries a nut or collar 19, preferably adjustable upon the rod, with which the latch 18 that has been referred to is adapted to engage; and, when such engagement takes place, the rod 17 is

held rigidly in locking position. A spring 20 connected with the latch 18 tends to move it into position to engage the collar 19. The latch is provided with a pin 21 with which 5 engages a cam 30 mounted upon the shaft 64 carrying the gears 12 and 13. The relations of the cam 30 and the pin 21 are such that when the parts of the batch timing mechanism are in normal position, as represented 10 in Fig. 4, the cam engages with the pin and rocks the latch 18, moving it out of engagement with the collar 19, thus leaving the rod 17 free to be moved, and hence unlocking the discharge chute; but when the parts are 15 moved to set the timing mechanism, Fig. 5, the cam 30 is disengaged from the pin and the latch 18 is freed and is immediately moved by the spring 20 into position to engage with the locking collar 19. If the discharge chute at this instance be in inactive, 20 non-delivery, position, it is immediately locked in that position. If, however, the chute C should happen to be in position to deliver material from the mixing drum the rod 17 will be raised with the collar 19 above the latch or trigger 18 and not engaged thereby, although the latter had moved into locking position. However, the trigger will 25 not interfere with the movement of the delivery chute to non-delivery position and the movement of the rod 17 downwardly under the driving force of the spring 22, as the pivoted latch 18 will yield to permit the collar 19 to pass its free end, and when this has 30 taken place the spring 20 will immediately restore the latch to its locking position, now above or in engagement with the collar.

In Fig. 1 I have shown the locking bolt or bar 17 connected with an extension rod 85 40 that is connected with a bell crank lever 84, which in turn is connected, by a link 83, with the control arm F of the power driven mechanism that moves the delivery chute arranged within the casing D. When the rod 17 is 45 locked, as has been described, the arm F cannot be shifted, and hence the delivery chute cannot be moved from its inactive to its delivery position.

In Fig. 2 is shown another arrangement by 50 which the delivery chute is locked. In this view the batch timing mechanism is represented as being mounted in close proximity to the casing D enclosing the power driven mechanism for operating the delivery chute 55 so that the locking rod 17 may extend directly from the casing E into the casing D and engage with an arm 60, connected with the control arm or handle F. In this instance the rod 17 is shown as provided with a tappet 60 arm 63, located without the casing D and arranged to be acted upon by a pin 62 carried by an eccentric or cam 61 that is supported upon the shaft h of the power driven mechanism for operating the discharge chute. 65 This shaft h is a part of the power driven

gearing that operates the discharge chute and when such mechanism is moved to put the chute into delivery position the rotating cam 61 occupies the position indicated in full lines, lifting the tappet arm 63 and the locking rod 17. But when the parts of the power driven mechanism are moved to shift the delivery chute into its inactive or non-delivery position, the cam 61 occupies the position shown in dotted lines, and then the rod 17 is free to fall and be locked as soon as the latch 18 is freed. 70

Still referring to Fig. 2, 45 indicates an arm that operates the clutch controlling the movements of the loading skip, and 46 an arm operating the brake that controls the downward movement of the loading skip. As represented, the arm 45 carries a contact piece 55 that is adapted to engage with an adjustable collar or nut 50 upon a rod 49 that is connected with a bell crank lever 48 which in turn is connected by a link or connecting rod 47 with the lever 2 of the batch timing mechanism. It will be seen that this arrangement of linkage between the lever 45 and the arm 2 takes the place of the push rod 1 operated directly by the loading skip and illustrated in Fig. 1. 75

In the illustration of my invention in Fig. 2 the batch timing mechanism is set as soon as the clutch lever 45 is moved and the loading skip commences its upward movement, while in the form of invention shown in Fig. 1 the setting of the batch timing mechanism does not take place until the skip has reached the end of its upward movement, and is in position to deliver its charge. 90

Referring again to Fig. 2 it will be seen that the brake control arm 46 is connected by a link 54 with a bell crank lever 52, the free end of which controls a latch 51 upon which acts a spring 53. The latch is in the path of the adjustable nut or collar 50 and is adapted to engage therewith and hold the linkage that is connected with the setting arm 2 of the batch timing mechanism in the position to which it may be moved by the lever 45 that controls the lifting of the loading skip, that is to say, holds the batch timer in its set position. When, however, the brake control arm 46 is moved the latch is retracted so as to disengage the collar 50, thus freeing the batch timing mechanism and allowing it to go through its movements. It will be seen that in both illustrations of my invention, as represented in Figs. 1 and 2 the batch timing mechanism is set when the mixing drum is being charged, and is released so as to begin its timing movement when the full charge from the loading skip has been delivered into the mixing drum, that is, when the loading skip begins its downward movement. 110

It will be seen that the mechanism employed to set the timing device comprises two independently movable parts—the shaft 64 115

and its associated parts, and the shaft 10 with its connections,—and that the two parts move together when the timing device is being set, but independently during their reverse movements; and also that one of the parts is arranged to operate the alarm or signal device at the starting of the timing operation, and the other part operates the alarm or signal at the close of the timing operation.

10 What I claim is:

1. The combination with mechanism whose operations are to be timed and an element operating preliminary to the commencement of the timing operation, of a timing device, 15 and means for setting the timing device, comprising two parts, one connected with the timing device and the other operated by the preliminarily operating element, the latter part moving the former to set the timing device 20 as the preliminary operation is taking place, and operating to positively maintain the timing device set until the preliminary operation is fully completed and then separating from and leaving it free after such preliminary operation, and a means for moving the timing device and the operating part connected with it which is set when the timing device is set, and operating the latter when it is freed.

30 2. The combination with mechanism whose operations are to be timed and an element operating preliminary to the commencement of the timing operation, of a timing device and means for setting it, comprising a shaft that 35 operates the timing device, another shaft operated by the preliminarily operating element, the second shaft moving the first as the preliminary operation is taking place, and operating to maintain the timing device in 40 set position until the preliminary operation is fully completed, but being disconnected therefrom and leaving it free after the preliminary operation is completed, and means for moving the said first shaft and timing device when the shafts are disconnected.

45 3. The combination with mechanism whose operations are to be timed and an element operating preliminary to the commencement of the timing operation, of a timing device, 50 and means for setting it, comprising a shaft that operates the timing device, another shaft operated by the preliminarily operating element, the second shaft moving the first as the preliminary operation is taking place, 55 and positively maintaining the timing device in set condition and against movement until the preliminary operation has been completed, but being disconnected therefrom and leaving it free after the preliminary operation is completed, a spring connected with the first mentioned shaft arranged to be put under tension when the timing device is set and serving to move the timing device upon the shafts being disconnected and the timing device released, and another spring connected

with the second mentioned shaft operating to disconnect the shafts.

4. The combination with mechanism whose operations are to be timed, and an element operating preliminary to the commencement 70 of the timing operation, of a timing device, a shaft arranged to have imparted to it a limited rotation by the said preliminarily operating element, a second shaft in alignment with the first and connected with the timing device 75 to operate it, means between the two shafts by which the first turns the second when moving in one direction, and positively maintains the timing device in set condition until its movement in said one direction is completed and the reverse movement begun, but disconnects therefrom on its reverse movement, and an operating spring connected with the second shaft put under tension when the said shaft is driven by the first and operating the timing device when the shafts are disconnected.

5. The combination with mechanism whose operations are to be timed, and an element operating preliminary to the commencement 90 of the timing operation, of a timing device, a shaft arranged to be moved through a limited range by the preliminarily operating element, a second shaft connected with the timing device to operate it, means between 95 the said shafts by which the second is driven by the first when moved in one direction, to set it and maintain it set during the full said movement of the shaft in one direction, but separating on the return movement of the first shaft, and means for returning the second shaft and thereby driving the timing device, at a relatively slow speed as compared 100 with the return movement of the first shaft.

6. The combination with mechanism whose operations are to be timed, and an element 105 operating preliminary to the commencement of the timing operation, of a timing device, means for setting it comprising two parts, one connected with the timing device and the other operated by the preliminarily operating 110 element, the latter moving the former to set the timing device when the preliminary operation takes place, and separating therefrom, leaving the timing device free to function, after such preliminary operation, a signal, 115 and means arranged to be operated by the means for setting the timing device for causing the signal to function, first when the two parts thereof separate, and again upon the completion of the timing operation.

7. The combination stated in claim 6, including a signal, arranged to be operated by the first named shaft on its reverse movement, indicating that the timing device has begun to function, and again operated from 125 the second shaft upon the completion of the operation of the timing device.

8. A mechanism for timing the operations of an apparatus, such as a mixing machine, comprising a shaft carrying a contact pro- 130

- jection, a second shaft in line with the first, carrying an arm adapted to be engaged by the said contact projection to cause rotation of the second shaft, a cylinder containing a 5 confined body of liquid and a piston moving in the cylinder and causing circulation of the liquid around the piston, gearing between the second shaft and the piston, a spring to move the second shaft and piston in one direction, and means for moving the first shaft rapidly to cause it to rotate the second shaft and for returning it, leaving the second shaft free to be moved more slowly by the spring. 10
9. The combination stated in claim 8, including also a signal device, and means for operating the signal arranged to be operated to give a signal upon the return movement of the first shaft, and also upon the completion of the movement of the timing mechanism. 15
10. The combination with a device for timing the operations of mechanism, of a disc arranged to have a limited rotative movement, the disc carrying a projecting pin, a shaft coaxial with the disc carrying an arm 20 lying adjacent to the disc and arranged to be acted upon by the pin projecting from the disc whereby the shaft is turned in one direction, a spring acting upon the shaft and arranged to be put under tension when the 25 shaft is turned by the movement of the disc, a timing mechanism geared with the shaft and arranged to be moved relatively slowly by the spring when free, and means for oscillating the disc at relatively high speed. 30
11. The combination with a device for timing the operations of mechanism, of a disc arranged to have a limited rotative movement, the disc carrying a projecting pin, a shaft coaxial with the disc carrying an arm 35 lying adjacent to the disc and arranged to be acted upon by the pin projecting from the disc whereby the shaft is turned in one direction, a spring acting upon the shaft and arranged to be put under tension when the 40 shaft is turned by the movement of the disc, a timing mechanism geared with the shaft and arranged to be moved relatively slowly by the spring when free, means for oscillating the disc at relatively high speed, and signal operating mechanism having a part in 45 engagement with the disc and actuated thereby on its return movement after it has moved the shaft and put the spring under tension, and arranged also to be actuated by the arm of the shaft upon the completion of 50 the timing operation. 55
12. The combination with mechanism whose operations are to be timed, of a timing device, a shaft that operates the timing device, a spring connected with said shaft, a second shaft arranged to move the first when turned in one direction, means for oscillating the second shaft in one direction to turn the first shaft and put the spring thereof 60 under tension, a spring connected with the second shaft and put under tension when it is oscillated as described, and means for shifting the connection of the said spring with its shaft as it is oscillated to put increased tension upon the spring, the latter spring 65 serving to rapidly move the second shaft on its return oscillation, and cause disconnection between the two shafts, leaving the first shaft free to be turned slowly by its spring to cause the timing device to function. 70
13. The combination of a timing device for a concrete mixing machine or other apparatus, a spring for moving the timing device, gearing through which the spring acts to operate the timing device, means for setting the timing device and putting the spring 75 under tension, a casing in which the enumerated devices are supported, a rod mounted within the casing and extending to the exterior thereof and arranged to function during the operation of the timing device, a pivoted latch arranged to act upon the rod and hold it against movement, a spring tending to move the latch into position engaging the rod and means carried by the gearing 80 for acting on the latch to move it into position to release the rod when the timing device completes its movement. 85
14. A batch meter comprising a cylinder in which is confined a body of liquid, having a longitudinal bore, a piston working in the bore of the cylinder, a by-pass between the opposite ends of the piston, a valve in the by-pass for restricting the flow of liquid through it, there being a valve controlled passage 90 through the piston permitting free flow of the fluid in one direction but obstructing the flow in the opposite direction, and there being a radial opening through the piston communicating with the passage through it, and another opening, in the cylinder, connecting the by-pass with the longitudinal bore of the cylinder, these openings being arranged to register with each other as the piston approaches the limit of its movement in the 95 direction opposed by the liquid having to pass through the restricted by-pass, whereby when they register the restricted portion of the by-pass is cut out and the circulation of liquid is free, permitting the piston to finish its movement rapidly, and a spring acting on the piston to move it in the direction herein referred to. 100
15. In a timing device adapted for use on concrete mixers, a dash pot, a coiled torsion spring, a gear train between said spring and the piston of the dash pot, means to put the spring under tension and to set the timing device and means to release the spring to permit it to operate the timing device. 105
16. A timing device adapted for use on concrete mixers comprising a dashpot with a cylinder and a piston working therein to circulate a confined body of fluid, a train of 110 gearing mounted on the dashpot, a coiled 115
17. A timing device adapted for use on concrete mixers comprising a dashpot with a cylinder and a piston working therein to circulate a confined body of fluid, a train of 120 gearing mounted on the dashpot, a coiled 125
18. A timing device adapted for use on concrete mixers comprising a dashpot with a cylinder and a piston working therein to circulate a confined body of fluid, a train of 125

spring supported on the cylinder and connected into the gear train, and means for placing the spring under tension, the spring when under tension operating through the gear train to retract the piston of the dashpot and when released to move it against the fluid within the dashpot that opposes the movements of the piston.

17. The combination of a device for timing apparatus arranged to be set and when released to run for a determined period, comprising a dash pot, a torsion spring, a gear train between the spring and the piston of the dash pot, a spring-actuated rod, a latch for engaging with the rod and preventing its movement, means to put the said torsion spring under tension and set the timing mechanism, means to release the timing mechanism to permit it to function, and means operated from the said gear train to move the latch into operative engagement with the rod while the timing device is functioning.
